ORDNANCE

John C. Trotter, Williamsville, N. Y., assignor to
Bell Aircraft Corporation, Buffalo, N. Y.

Application March 16, 1942, Serial No. 434,826

7 Claims. (Cl. 89—33)

This invention relates to ordnance, and more particularly to improvements in ammunition feed mechanisms of the Chatellerault feed mechanism type for use in conjunction with rapid fire or machine guns, automatic cannon, or the like.

One of the objects of the invention is to provide a feed mechanism for the purpose referred to which is adapted to be employed in improved manner as an accessory to any standard type of automatic fire arm for substantially relieving the usual feed pawl mechanism thereof of the loads incidental to elevating the ammunition to the level of the gun and accelerating movement of the ammunition belt toward the gun in connection with recommencement of gun firing operations. Another object of the invention is to provide an improved ammunition feed device for automatic firearms which is adapted to receive a belt of linked ammunition and to disassociate the links from the rounds in improved manner prior to delivery of the rounds into the ammunition feedway of the gun. Another object of the invention is to provide an ammunition feed mechanism of the character described which is adapted to operate with equal facility in conjunction with ammunition rounds having projectile or nose end portions of various lengths. Other objects and advantages of the invention will appear in the specification hereinafter.

In the drawings:

Fig. 1 is a transverse section through an ammunition feed mechanism of the invention;

Fig. 2 is a section through the mechanism of Fig. 1 taken along line II—II thereof, and indicating an automatic firearm disposed in operative relation therewith;

Fig. 3 is an end elevation of the mechanism of Figs. 1 and 2;

Fig. 4 is a fragmentary sectional view along line IV—IV of Fig. 1, showing the ammunition rounds and belt link segregating mechanism of the invention;

Fig. 5 is a bottom plan of a group of shells and their associating links showing the relationships of the rounds and links at various stages of the rounds and links segregating operation of the invention; and

Fig. 6 is a fragmentary section taken along line VI—VI of Fig. 4.

The invention is illustrated in the drawings as being arranged in conjunction with an automatic firearm indicated generally at 10 (Fig. 2) having the usual ammunition feedway port at 12. The ammunition feed device of the invention comprises generally a self-contained unit which

is illustrated in Figs. 1 to 3 as being housed in a cylindrical casing 14. A cartridge belt inlet port is provided at 16 for training of a linked cartridge belt thereinto, and an ammunition outlet port 18 is provided at the opposite side of the casing for registry with an ammunition feed conduit 20 leading to the ammunition feedway portion 12 of the associated gun.

The figures illustrate the mechanism in operation in connection with rounds of ammunition designated 22 which are connected in articulated relation by means of links 24 to provide a continuous cartridge belt. The links 24 are of the conventional open side type whereby the cartridge belt may be disintegrated upon backward shifting of the cartridges relative to the links in directions parallel to the longitudinal axes of the cartridges, whereby lesser diameter portions of the cartridges register with the side openings in the links to permit lateral withdrawal of the cartridges from the links. As will be explained more fully hereinafter, a reel device is mounted within the casing 14 so as to be freely rotatable therein and is formed with sprocket wheel portions to engage the cartridge belt in geared relation therewith for pulling the belt into the feed mechanism prior to disintegration of the belts and feeding of the cartridges to the associated gun.

An electric motor 30 is mounted upon one end 30 of the casing 14 by having an enlarged housing portion 32 thereof tight-fitted telescopically within the adjacent end portion of the housing 14. Preferably, the housing is split and perforated as indicated at 33 to carry a screw or bolt 35 for detachably clamping the split end portion of the housing upon the motor case. An end bell of the motor 30 is indicated at 34 as extending inwardly of the housing 14, and the motor shaft is indicated at 36. The motor shaft 36 is formed 40 for spline connection with a driving cup 38 having a cylindrical wall portion 39 extending about the motor end bell so as to be free fitting relative thereto. A clock-type spring 40 is mounted about the cup portion 39 and keyed thereto at its inner 45 end so as to be carried with the cup as it rotates upon operation of the motor 30. The outer end of the spring 40 is connected to a second or driven cup 42 which is reduced at its inner end portion to telescopically engage the corresponding reduced end portion of the driver cup 38. A bushing 44 is disposed between the corresponding reduced end portions of the cups 38—42 to provide a suitable reduced friction bearing arrangement therebetween.

55 The outer surface of the cup 42 engages a ball-

bearing device as indicated at 46 which is mounted upon a transverse partition portion 47 of the housing 14, whereby the cup 42 is freely rotatable relative both to the cup 38 and to the housing 14. An extension shaft 50 is mounted in spline connection relation at one end within the reduced end of the cup 38, and the shaft 50 is rotatably mounted adjacent its opposite end by means of a bushing 52. The bushing 52 is carried by a thimble 54 which is rotatably mounted relative to the housing 14 by means of a ballbearing device 56. Thus, the extension shaft 50 is keyed to the cup 38 and thereby to the motor shaft 36 so as to be functionally integral therewith subsequent to assembly of the mechanism.

A cylindrical reel 60 is mounted at its opposite ends upon the thimble 54 and upon the reduced end portion of the cup 42; and the reel is keyed to the cup 42 by means of set screws 62. The reel is provided approximately midway of its length with a pair of spaced integral sprocket wheel formations having teeth 64-65 extending radially therefrom for geared engagement with the cartridge belt entering the feed device. Thus, the teeth 64-65 are so relatively spaced and shaped as to be adapted to mesh between successive cartridges 22 of the cartridge belt as it enters the inlet port 16 of the mechanism, as illustrated at the right hand side of Fig. 2; and it will be understood that whenever the reel 60 is driven to rotate in counterclockwise direction as viewed in Fig. 2 the reel will thereby pull the cartridge belt into the feed device for delivery of the ammunition rounds 22 to the associated gun subsequent to segregation of the cartridge belt links from the rounds, as will be explained hereinafter.

An automatic motor control mechanism is arranged in conjunction with the reel device, and comprises a nut 70 which is mounted upon a screw threaded end portion 72 of the shaft 50. The nut 70 is axially slotted at its outer surface to engage in spline connection relation at 74 with correspondingly slotted portions of the thimble 54, the latter being fixed for rotation with the reel 60. Thus, it will be understood that upon relative rotational movement between the thimble 54 and the shaft 50 the nut 70 will be displaced axially, either to the right or to the left as viewed in Fig. 1, depending upon the direction of relative rotation between the parts. A yoke arm 76 extends at one end into registry with the path of axial movement of the nut 70 and is pivoted at 77 intermediately of its ends upon a fixed end plate portion 78 of the housing 14. At its opposite end the arm 76 carries an actuating finger 79 for operating a micrometer switch 80 which is mounted upon the housing 14 and is electrically connected in the power supply circuit of the motor 30 so as to control operation of the latter. The switch 80 and control arm 76 are so provided and arranged that whenever the nut 70 travels to the left as viewed in Fig. 1 and presses the adjacent end of the arm 76 outwardly the micrometer switch 80 is actuated to open condition; and reversely, when the nut 70 moves toward the right the micrometer switch is actuated to circuit-closed condition. A ratchet wheel 82 is keyed to the outer end of the shaft 50 and a pawl 84 is pivoted upon the housing end wall at 85 and backed by a spring 86 to engage the ratchet 82 in such manner as to prevent rotation of the shaft 50 in reverse direction upon deenergization of the motor 30.

Thus, it will be understood that the cartridge

belt driving mechanism will operate as follows. When the electric power supply circuit of the motor 30 is closed the motor 30 will drive the shaft 50 to rotate in counterclockwise direction as viewed in Figs. 2 and 3. As explained hereinabove, the motor shaft 36 and extension shaft 50 function as an integral assembly because of their common connection to the cup 38. The cup 38 is simultaneously rotated in the same direction and thereby drags upon the inner end of the clock spring 40 whereby the motor torque is transmitted to the outer cup 42 which is keyed directly to the reel 60. Consequently, as soon as the operation of the mechanism has suitably tensioned the spring 40 the reel 60 will be rotating with the motor extension shaft 50 in the same direction and at equal rate for drawing the cartridge belt through the inlet port 16 of the feed mechanism. Upon stopping of the gun firing operation, either intentionally or because of jamming of the cartridge belt or gun mechanisms, the reel 60 will be stopped because of its geared engagement with the cartridge belt while the motor 30 continues temporarily to drive the extension shaft 50. The rotational differential between the cups 38-42 will be absorbed by additional tensioning of the spring 40 while the shaft 50 rotates relative to the thimble 52 which is carried by the reel. Consequently, the nut 70 is thereby caused to be displaced to the left as viewed in Fig. 1, thereby actuating the lever 78 to adjust the micrometer switch 80 to open the power supply circuit of the motor 30. Thus, the reaction by the spring 40 against the motor rotation subsequent to stoppage of the reel 60 will resiliently oppose the motor and stop it as the electrical power supply circuit is opened, whereby damage to the motor windings will be avoided. Upon final stopping of the motor operation the ratchet pawl 84 will act to hold the motor shaft 50 against reverse rotation such as would otherwise relax the spring 40. Therefore, the spring 40 will be then pretensioned so that whenever the gun firing operation is recommenced and the reel 60 is released the spring will be adapted to impart to the cartridge belt driving mechanism a spontaneous acceleration force functioning to drive the cartridge belt toward the gun. The nut 70 will be concurrently displaced axially toward the right as viewed in Fig. 1 because of the rotational differential between the reel thimble 54 and the shaft 50, and so the switch 80 will be actuated to close the circuit of the motor 30. Thus, during the initial acceleration period of the motor operation wherein the motor is operating at less than normal speed the above-normal tensioning of the spring 40 will operate as explained hereinabove to provide instantaneous feeding of the cartridge belt, and throughout the operating cycle of the mechanism control of the motor 30 is completely automatic.

Thus, it will be understood that the cartridge belt driving mechanism of the invention comprises a novel self-contained accessory unit 65 which normally drives the cartridge belt to move in the direction of the associated gun in accord with the feed requirements thereof, and which embodies novel and important jam accommodating features whereby damage to the motor and driving mechanisms in connection with stoppages of the gun firing operation for various reasons are avoided, and whereby the mechanism is automatically preloaded at the end of each operating cycle so as to be prepared to apply acceleration forces to the cartridge belt upon recommence-

ment of the firing operation, in improved manner.

The mechanism of the invention also embodies novel means for segregating the shell or cartridge belt links from the ammunition rounds subsequent to feeding of the belt into the mechanism and prior to delivery of the rounds to the associated gun. The sprocket formations 64-65 of the reel device are so spaced along the longitudinal axis of the reel as to be adapted to receive therebetween the ammunition connecting links 24 as the cartridge belt enters the inlet port 16 of the device. Thus, the links 24 are held by the sprocket formations against movement axially by the rounds subsequent to entry of the links into the feed mechanism.

The reel 60 is provided with a plurality of rounds shifting devices arranged to lie peripherally of the reel and in radially spaced relation thereabout so as to be adapted to individually engage successive cartridges of the cartridge belt as they enter the device. Each cartridge shifting device comprises a shaft 90 mounted by means of spaced bearing portions of the reel so as to be disposed parallel to the axis of the reel and to be freely slideable relative thereto in longitudinal directions. A cartridge engaging head 92 is carried by each of the shafts 90 by being pinned thereto as at 93, and a ball bearing 94 is carried upon each cartridge engaging head by means of a pin 95 so that the roller is adapted to engage in bearing relation against a circuitous cam surface portion 96 of the housing 14. A compression spring 97 is arranged in conjunction with each of the shafts 90 to urge the latter to move toward the left relative to the reel as viewed in Fig. 1, so that the ball bearing members 94 will bear in camming relation against the cam surface 96 as the reel rotates about the axis of the motor shaft 50.

The cam surface 96 is so formed as to cause the cartridge shifting shaft members 90 to be forced to positions of maximum retreat as they come into registry with the inlet port 16 of the feed mechanism. Each cartridge engaging head member 92 is generally in the form of a cradle adapted to complement and embrace the adjacent curved surface portion of a cartridge or shell case, and a lever 98 having an outturned end portion is pivotally mounted upon each of the heads, as at 99. A compression spring 100 is provided to bias each of the levers 98 outwardly so that their fingers will engage within the conventionally provided extracting grooves of the cartridge cases at the primer ends thereof as the cartridges are received by the corresponding head members 92. Thus, as each successive cartridge enters the feed device it is engaged by the head 92 of one of the shafts 90, and the corresponding finger 98 enters the extracting groove of the cartridge for fixing the cartridge longitudinally relative to the cartridge shifting mechanism. As the reel 60 rotates away from the inlet port 16 the cam surface 96 retreats, as indicated diagrammatically at 102 in Fig. 1, to permit the cartridge shifting mechanism to advance toward the left as viewed in Fig. 1 to a position of maximum advancement when the corresponding cartridge reaches a position of registry with the outlet port 18 of the feed mechanism housing.

As explained hereinabove, the sprocket portions 64-65 of the reel device maintain the cartridge connecting links 24 against shifting in directions axially of the reel as the reel rotates. Thus, as

the cartridge shifting devices move from retreated to advanced positions while being rotated between the positions of the ammunition inlet and outlet ports, the corresponding cartridges are automatically shifted rearwardly relative to their connecting links so as to become completely disconnected therefrom (Fig. 5). Consequently, when the cartridges reach positions of registry with the outlet port 18 of the mechanism they are free from connection with the cartridge belt links and are thereby adapted to be scooped out of engagement with the reel 60 by means of a scoop plate 104 (Fig. 2) so as to be guided thereby into the outlet conduit 20 for feeding the associated gun. Thus, in summary, it will be understood that as the reel 60 rotates it draws the cartridge belt into the housing 14; disconnects the successive cartridges from the connecting links 24; and then pushes the freed cartridges into the outlet conduit 20 and into the feedway port of the gun, at a rate equal to the ammunition feed requirements of the gun.

To lift the links 24 out of alignment with the corresponding ammunition rounds subsequent to disconnection of the links and rounds, each of the cartridge shifting shaft members 90 carries at its inner end an abutment block 106. The blocks 106 are adapted to bear against the ends of corresponding bell crank levers 108 which are pivoted upon the reel 60 so as to bear upwardly against the corresponding links 24 as the cartridges are shifted axially relative to the links 24 as explained hereinabove. Therefore, as the successive cartridges become finally freed from the links and move through the outlet port 18 the corresponding lift cranks 108 elevate the links so that they are caught upon a scoop plate 110 and directed into a link discharge port 112 of the casing wherefrom they are finally disposed of in any desired manner.

Thus, it will be seen that the cartridge shifting mechanism functions automatically throughout the entire cycle of link segregating and cartridge feeding operation as the reel 60 rotates within the housing; and that a particular feature of the invention resides in the fact that the entire link segregating operation is controlled by the action of the cam surface 96 upon the cartridge shifting members which engage successive rounds at their head ends. Thus, the mechanism relies in no respect for its proper operation upon engagement of the nose or projectile end portions of the rounds against any camming or guiding devices, whereby effective operation of the mechanism is provided at all times irrespective of the fact that the nose or projectile ends of the rounds may be of varying lengths. This is a particularly important feature in view of modern combat practices which often dictate feeding of rapid firing guns alternately with projectile and tracer and armor piercing rounds or the like, whereby the lengths of the nose portions of the rounds being handled will vary considerably throughout a single gun firing operation.

Although only one form of the invention has been shown and described in detail, it will be apparent to those skilled in the art that the invention is not so limited but that various changes may be made therein without departing from the spirit of the invention or the scope of the appended claims.

I claim.

1. An ammunition feed mechanism for use in feeding successive rounds of ammunition to a gun from an integrating link cartridge belt, said

mechanism comprising a casing having an ammunition belt inlet port and a link discharge portion, a reel rotatably mounted within said casing and having teeth portions extending therefrom for engagement in geared relation with the feeding ammunition belt, said casing having an ammunition outlet port opposed to said inlet port, means on said reel for maintaining the ammunition belt forming links against displacement in directions axially of the reel as said links engage said reel, means carried by said reel for separately engaging successive ammunition rounds at the primer end portions thereof as they enter said casing and moving said rounds rearwardly relative to their corresponding links for disengagement of said rounds from said links prior to rotation of said rounds by said reel into positions of registry with said outlet port, and means carried by said reel to bear against said links subsequent to disengagement thereof from the corresponding ammunition rounds for displacing said links out of registry with said ammunition outlet port and in registry with said link discharge portion of said casing whereby said links are prevented from entering said outlet port with said rounds. 25

2. An ammunition feed mechanism for use in feeding successive rounds of ammunition to a gun from an integrating link cartridge belt, said mechanism comprising a casing having an ammunition belt inlet port, a reel rotatably mounted within said casing, said casing having an ammunition outlet port opposed to said inlet port, means on said reel for maintaining the ammunition belt forming links against displacement in directions axially of the reel, finger means slidably mounted upon said reel for separately engaging successive ammunition rounds at the primer end portions thereof as they enter said casing, cam means formed on said casing for cooperating with said finger means for actuating the latter so that said rounds are caused to move backwardly relative to their corresponding links for disengagement of said rounds from said links while said rounds are being carried by said reel into positions of registry with said outlet port, and means carried by said reel to displace said links radially outwardly therefrom to cause the latter to be dissociated from said rounds subsequent to disengagement thereof whereby said links are prevented from entering said outlet port with said rounds. 50

3. An ammunition feed mechanism for use in feeding successive rounds of ammunition to a gun from an integrating link cartridge belt, said mechanism comprising a casing having an ammunition belt inlet port, a reel rotatably mounted within said casing, said casing having an ammunition outlet port opposed to said inlet port, means on said reel for maintaining the ammunition belt forming links against displacement in directions axially of the reel, finger means slidably mounted upon said reel for separately engaging successive ammunition rounds at the primer end portions thereof as they enter said casing, cam means formed on said casing for cooperating with said finger means for actuating the latter so that said rounds are caused to move backwardly relative to their corresponding links for disengagement of said rounds from said links while said rounds are being carried by said reel into positions of registry with said outlet port. 70

4. An ammunition feed mechanism for use in feeding successive rounds of ammunition to a gun from an integrating link cartridge belt, said

mechanism comprising a reel rotatably mounted upon a support and having teeth portions extending therefrom for engagement in geared relation with an ammunition belt when wrapped about said reel for feeding in the direction of said gun, means on said reel for maintaining the ammunition belt forming links against displacement in directions axially of the reel as said links engage said reel, means carried by said reel for separately engaging successive ammunition rounds at the primer end portions thereof as they engage said reel and moving them backwardly relative to their corresponding links for disengagement of said rounds from said links prior to discharge of said rounds by said reel into position for feeding said gun. 10

5. An ammunition feed mechanism for use in feeding successive rounds of ammunition to a gun from an integrating link cartridge belt, said mechanism comprising a casing having an ammunition belt inlet port, a reel rotatably mounted within said casing, said casing having an ammunition outlet port opposed to said inlet port, means on said reel for maintaining the ammunition belt forming links against displacement in directions axially of the reel, finger means slidably mounted upon said reel for separately engaging successive ammunition rounds at the primer end portions thereof as they enter said casing, cam means formed on said casing for cooperating with said finger means for actuating the latter to move the cartridges backwardly relative to their corresponding links for disengagement of said rounds from said links while said rounds are being carried by said reel into positions of registry with said outlet port, and means carried by said reel to displace said links radially outwardly therefrom to cause the latter to be dissociated from said rounds subsequent to disengagement thereof whereby said links are prevented from entering said outlet port with said rounds, said link displacement means comprising corresponding lever devices pivotally mounted upon said reel and operable to lift said links as the corresponding rounds are disengaged therefrom. 30

6. An ammunition feed mechanism for use in feeding successive rounds of ammunition to a gun from an integrating link cartridge belt, said mechanism comprising a casing having an ammunition belt inlet port, a reel rotatably mounted within said casing and having teeth portions extending therefrom for engagement in geared relation with the feeding ammunition belt, said casing having an ammunition outlet port opposed to said inlet port, an electric motor mounted upon the said casing and having its drive shaft extending thereto, a clock-type spring encompassing said drive shaft and connected thereto at its inner end, said drive shaft extending concentrically with the axis of said reel, means extending from said reel into connection with the outer end of said spring, and ratchet means interconnecting said drive shaft and said casing to permit said drive shaft at all times to rotate relative to said reel in such a manner as to tension said spring but to prevent said drive shaft from rotating in reverse direction in response to forces of said spring upon deenergization of said motor, and motor control means comprising a nut mounted in screw threaded rotation upon said drive shaft and arranged in spline connection with said reel and operable in response to relative rotation of said drive shaft and said reel to move axially of said drive shaft to operate a motor power circuit control switch between open and closed positions. 50

7. An ammunition feed mechanism for use in feeding successive rounds of ammunition to a gun from an integrating link cartridge belt, said mechanism comprising a casing having an ammunition belt inlet port, a reel rotatably mounted within said casing and having teeth portions extending therefrom for engagement in geared relation with the feeding ammunition belt, said casing having an ammunition outlet port opposed to said inlet port, and a link discharge port adjacent said ammunition outlet port but separate therefrom, means on said reel for maintaining the ammunition belt forming links against displacement in directions axially of the reel as said links engage said reel, means carried by said reel for separate-

15

ly engaging successive ammunition rounds at the primer end portions thereof as they enter said casing for pulling said rounds backwardly relative to their corresponding links for disengagement of said rounds from said links prior to rotation of said rounds by said reel into positions of registry with said outlet port, means carried by said reel to bear against said links to cause the latter to separate from said rounds upon disengagement therefrom and to be displaced into registry with said link discharge port whereby said links are prevented from entering said ammunition outlet port with said rounds.

JOHN C. TROTTER.
